UNITED STATES PATENT OFFICE.

J. WESLEY WEBBER, OF NEW YORK, N. Y.

DRILL.

SPECIFICATION forming part of Letters Patent No. 252,161, dated January 10, 1882.

Application filed January 3, 1876. Renewed October 25, 1880. Again renewed June 13, 1881. (Model.)

To all whom it may concern:

Be it known that I, J. WESLEY WEBBER, of New York, N. Y., have invented an Improvement in Drills, of which the following is a specification.

The object of my invention is to so construct a machine that it will drill holes of various shapes and sizes and cut out pieces of various shapes and sizes, accomplishing the same by positive motion.

Figure 1 represents the working parts of my invention complete and together. C C is a slide working in a frame, N N. E is an oval plate fixed to the under side of the upper cross-piece of the slide C. A is the driving shaft, passing downward through the cross-piece B of the frame N N and through the upper cross-piece of the slide C and plate E, extending through and projecting from the lower cross-piece of the slide C. It is slotted at its lower end, as shown in Figs. 2 and 4. a a represent the pattern-plates, (see Figs. 5 and 6,) to be fastened under the plate E by the thumb-screws R R, (shown by dotted lines, Figs. 1 and 2,) which hold the pattern-plates in the position shown against a pin with a T-shaped head projecting through the holes P P. When held in this position the slot L forms a square or a circle, as the case may be. K K represent sent cutters running through and working in the slot in the lower end of shaft A, both of which are pivoted on the pin D. S S indicate two slotted arms fixed to shaft A, through which the cutters K K work as their upper end travels in the slot L. J represents a half journal-box, attached by means of the screws shown, and removable so as to fit various-shaped cutters in the slotted shaft A.

Fig. 2 is a side view of my machine.

Fig. 3 represents cutters (in position for work) 40 of different spread at the lower end for the purpose of cutting out pieces for making larger holes.

Fig. 4 represents the shaft, showing the slot in the lower end, in which the cutters K K 45 work. M indicates a thread, upon which, after the removal of the cutters K K, a common drill-chuck can be fitted to receive the common drill.

Figs. 5 and 6 represent the pattern-plates 50 with the slot L cut therein, in which the cutters K K work. (See Fig. 1.) Said pattern-plates are in two pieces or sections, and are fitted around the shaft from opposite directions, and held by the T-shape headed pins and 55 thumb-screws R, as shown in Fig. 1. H H indicate threaded holes, in which the thumb-screw R fits. (See Figs. 1 and 2.) P P show the holes through which the T-shape headed pins project from plate E, and assist to hold 60 the pattern-plates, as shown in Fig. 1.

By imparting a rotary motion to shaft A the upper end of the cutters K K are carried by positive motion in the slot L. A similar motion is imparted to the lower end of the 65 cutters, which cut the desired-shaped hole or piece.

I claim as my invention—

The combination, with the drill-shaft and the pattern-cam, of the cutters and cutter-levers, 70 connected to one another and to the drill-shaft by a single pivot, and the slotted arms S, substantially as described.

J. WESLEY WEBBER.
